UNITED STATES PATENT OFFICE.

CHARLES HORACE BOWMAN, OF BERLIN, NEW JERSEY, ASSIGNOR TO BREUKER AND KESSLER COMPANY, OF PHILADELPHIA, PENNSYLVANIA, A CORPORATION OF PENNSYLVANIA.

DESIGN FOR BOX-COVERING PAPER.

No. 39,425.

Specification for Design.

Patented July 14, 1908.

Application filed April 21, 1908. Serial No. 428,461. Term of patent 3½ years.

To all whom it may concern:

Be it known that I, CHARLES HORACE BOWMAN, a citizen of the United States, residing at Berlin, county of Camden, and State of New Jersey, have invented a new, original, and ornamental Design for Box-Covering Paper, reference being had to the accompanying drawings for an illustration of the same.

The figure represents the design as applied to a section of the paper.

I claim:

The ornamental design for box covering paper, as shown.

CHARLES HORACE BOWMAN.
